CLAIM

The ornamental design for a baler with reservoir tank, as shown and described.

DESCRIPTION

FIG. 1 is a front perspective view of a baler with reservoir tank according to our new design shown with symbolic breaks in the height, width and depth of the baler;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The evenly dashed lines in the figures depict environmental features and portions of the article that form no part of the claimed design. The unevenly dashed lines in FIGS. 1-7 represent symbolic breaks across the height, width and depth of the baler and the appearance of the baler between the break lines forms no part of the claimed design.
